(57) **CLAIM**

The ornamental design for an ultrasonic cutter head for medical purpose, as shown and described.

DESCRIPTION

FIG. 1 is a perspective view of an ultrasonic cutter head for medical purpose showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate structure or features which form no part of the claimed design.

The six circles shown in the right side view are apertures that connect to the six circles in the left side view.
